103,646

DESIGN FOR A GAME DEVICE

Lawrence W. Van Ore, Rochester, N. Y.

Application December 11, 1936, Serial No. 66,488

Term of patent 3½ years

To all whom it may concern:

Be it known that I, Lawrence W. Van Ore, a citizen of the United States, residing at Rochester, in the county of Monroe and State of New York, have invented a new, original, and ornamental Design for a Game Device, of which the following is a specification, reference being had to the accompanying drawing, forming part thereof.

I claim:

The ornamental design for a game device, as shown.

LAWRENCE WM. VAN ORE.
